(57) **CLAIM**

I claim the ornamental design for a bratwurst grilling roller,
as shown and described.

DESCRIPTION

FIG. 1 is a front elevation view of the bratwurst grilling roller showing my new design, the rear view being a mirror image;

FIG. 2—is a right side elevation view thereof,

FIG. 3—is a left side elevation view thereof,

FIG. 4—is a plan view of the bottom of the ornamental
design for a bratwurst grilling roller,

FIG. 5—is a top plan view thereof,

FIG. 6—is a perspective elevation view thereof; and,

FIG. 7—is a setting for the ornamental design for a
bratwurst grilling roller.

The broken lines in FIG. 7, are for illustrative purposes only,
and form no part of the claimed design of this invention, for
ornamental design for a bratwurst grilling roller.
